ATTORNEY.

UNITED STATES PATENT OFFICE.

SIDNEY OSTROFF, OF LOWELL, MASSACHUSETTS.

GAS MIXER.

Application filed July 8, 1925. Serial No. 42,202.

This invention relates to gas mixers for internal combustion engines and has for an object to provide new and improved type of apparatus for commingling and intermixing 5 heated gases from the exhaust with the incoming gasoline vapor before introducing into the carburetor for mixing with the required charge of air.

A further object of the invention is to provide in a gas mixer communicating chambers through which successively the gasoline vapors pass and in the latter of which the vapors are intimately intermixed with hot gases from the exhaust manifold and from 15 which latter chamber the gases so mixed pass to a carburetor.

A further object of the invention is to provide communicating, preferably approximately spherical, chambers through which 20 gasoline passes successively, in the latter chamber being subjected to an agitator operated by the introduction of heated gases from the exhaust manifold under pressure to commingle with the passing gasoline vapors 25 with a thorough intermixing produced by the agitator.

With these and other objects in view, the invention comprises certain novel parts, elements, units, combinations, constructions, interactions and functions as disclosed in the drawings together with mechanical and functional equivalents thereof as will be hereinafter more fully described and claimed.

In the drawings:

Figure 1 is a view of the gas mixer in side elevation.

Figure 2 is a diametrical sectional view through the gas mixer taken on line 2—2 of Figure 1.

Figure 3 is a transverse sectional view through the agitating chamber taken on line 3—3 of Figure 2.

Like characters of reference indicate corresponding parts throughout the several views.

The improved gas mixer which forms the subject matter of this application comprises chambers A and B, preferably though not necessarily approximately spherical. These 50 chambers A and B communicate with each other in any approved manner as by a conduit 10 which is formed through a threaded shank 11 which is formed upon the wall of one of the chambers, as the wall 12 of the chamber B. The wall of the other cham-

ber, as the wall 13 of the chamber A, is screw threaded as at 14, to engage on said threaded shank 11.

The chambers A and B are respectively made up of walls of separable sections, the 60 walls 12 and 13 having already been noted, the other sections 12' and 13' being connected with the sections 12 and 13 in any approved manner as by forming flanges or ears 15 and employing screws or bolts 16 for 65 holding the substantially semi-spherical sections together. For the purpose of making gas tight joints, gaskets 17 are employed.

The chamber A is in communication, when in use, with the source of gasoline supply 70 as the vacuum tank and a pipe 18 is shown in the drawings for the purpose of conducting the gasoline from such source to the chamber A. It is to be understood that the relative length or size of this pipe 18 and the connection 19 shown thereon are only 75 illustrative and will be varied according to the necessities of installation. The pipe is connected with the chamber A by means of the connection 20, no novelty being 80 claimed for this connection as it is of an ordinary well known type. The chamber A is merely a hollow, substantially spherical, chamber, while the chamber B is provided with an agitator. The agitator is in the 85 form of a fan 21 which is mounted to rotate upon an axis substantially in alignment with the conduit 10. For convenience of mounting the agitator, a collar 22 is introduced into proper furrows in the sections 12 and 12' of the chamber B so that, when the sections 12 and 12' are secured together by the bolts or screws 16, the collar 22 is held firmly in position. Cross pieces 23 are provided for holding a journal pin 24.

For the purpose of rotating the agitator 21, an inlet 25 is provided normally in communication with the exhaust manifold, a check valve 26 being provided to prevent back pressure from returning through the 100 exhaust manifold to carry gases from the chamber B to exhaust. For connecting with the carburetor, a connection 27 is also provided, it being understood that the particular type of connection both at 27 and at 26 105 forming a part of the check valve will vary as required by the particular installation.

Also a collar 28 with wings 29 or other appropriate means for attaching the device to the dash or other parts of a car or instal- 110

lation will be provided, it also being only illustrative and varying with the particular type of installation.

In operation, the heated gases from the exhaust entering through the conduit 25 heats the chamber B and communicates its heat also to the chamber A. Gasoline entering through the tubing 18 or the equivalent into the chamber A is subjected to this heat in the chamber A and vaporized, passing thence through the conduit 10 into the chamber B. In this chamber B the vaporized gasoline from the chamber A is intermixed with the heated gases from the manifold introduced through the conduit 25, such gases by being introduced at the angle indicated at Figure 1, rotating the agitator 21 to thoroughly intermix said exhaust gases and the gasoline vapor, which intermixed gases pass outwardly through the connection 27 to the carbureter where they are mixed with the air in proper proportions in the usual well known manner.

What I claim to be new is:

1. A fuel volatilizer comprising a primary chamber constructed substantially as a sphere with polar conduits communicating therewith, one of which is adapted for con-

nection to a carbureter, a mechanical agitator within said chamber moving upon an axis coinciding with the pole of the sphere, an inlet conduit for heated gases communicating with the chamber at a tangent and at an inclination to the equatorial plane, a second chamber communicating with the first mentioned chamber through one of the polar conduits, and means to introduce liquid fuel into the last mentioned chamber.

2. A fuel volatilizer comprising a substantially spherical chamber having polar conduits, a fan located within the chamber with its axis coinciding with the pole and rotating in a substantially equatorial plane, a secondary chamber communicating with the first mentioned chamber through one of the polar conduits, means to introduce a liquid fuel into the last mentioned chamber, means to introduce a heated gas into the first mentioned chamber at an inclination to the plane of the fan, and means communicating with the polar conduit opposite the second mentioned chamber to conduct the mixed gases to a carbureter.

In testimony whereof I affix my signature.

SIDNEY OSTROFF.
